UNITED STATES PATENT OFFICE.

ARTHUR C. LAWS, OF FULTON, NEW YORK.

DESIGN FOR A MALLET.

43,877.

Specification for Design. Patented Apr. 22, 1913.

Application filed December 10, 1912. Serial No. 736,026. Term of patent 14 years.

To all whom it may concern:

Be it known that I, ARTHUR C. LAWS, a citizen of the United States, residing at Fulton, in the county of Oswego and State of New York, have invented a new, original, and ornamental Design for Mallets, of which the following is a specification, reference being had to the accompanying drawing, forming part thereof.

The figure is a perspective view of the mallet.

I claim:—

The ornamental design for a mallet, as shown.

ARTHUR C. LAWS.

Witnesses:

GEORGE W. PELTOM,
HORACE D. WADSWORTH.
